INVENTOR.

I. J. THOMSEN,
BY *Henry A. Mathews*

ATTORNEY.

UNITED STATES PATENT OFFICE.

INGEBERT J. THOMSEN, OF MINDEN, NEBRASKA.

PNEUMATIC HORSE COLLAR.

Application filed July 21, 1927. Serial No. 207,446.

My invention relates to improvements in pneumatic horse collars.

In accordance with my invention, I provide a horse collar embodying an outer casing, formed of leather or other suitable material. This casing is filled with inflated sacks or cells, arranged upon opposite sides of the neck of the horse. A combined inflating and air pressure retarding device connects the ends of the two cells. The device is so constructed that the two cells are in permanent communication with each other, through a contracted port or passage so that they may be simultaneously inflated to the same degree of pressure. However, the contracted port or passage will prevent the sudden rush of air pressure from one cell to the other, in the event that the load is suddenly shifted to one shoulder of the horse. The arrangement is such that the device may be covered by a flap, and will not interfere with the harness and will be protected.

In the accompanying drawings, forming a part of this specification, and in which like numerals are employed to designate like parts throughout the same,

Figure 1 is a front side elevation of a pneumatic collar embodying my invention,

Figure 2 is a similar view of the two cells included in the collar,

Figure 3 is an enlarged section through the lower ends of the cells, parts in elevation, and,

Figure 4 is a transverse section taken on line 4—4 of Figure 3.

In the drawings, wherein for the purpose of illustration, is shown a preferred embodiment of my invention, the numeral 10 designates the outer casing of a horse collar, which may be formed of leather or the like. This casing includes shoulder sections 11 to engage the opposite shoulders of the horse. The casing 10 is provided at its inner edge with a roll or bead 12, which may be stuffed with straw or the like. The usual strap means 13 is employed to connect the upper ends of the shoulder sections 11. The bead 12 and shoulder sections 11 are preferably continuous at the bottom.

The numeral 14 designates a pair of pneumatic sacks or cells, preferably formed of rubber, and of a shape, and size to fit within the shoulder sections 11. These cells are separate, as shown.

The numeral 15 designates a combined inflating and pressure retarding device, em-

bodying a tubular body portion 16 carrying at its ends necks 17, provided with radially projecting flanges 18. The lower ends of the cells 14 are adapted to be applied to the necks 17, and forced over the flanges 18, thus being securely held upon the necks and effecting air-tight joints. The cells 14 being separate, either may be removed, without disturbing the other. The tubular body portion 15 is provided in its upper portion with a forwardly extending horizontal screw-threaded bore 19, receiving a tubular member 20, having screw-threaded engagement therewith. The tubular member is internally threaded at 21 for engagement with the screw-threaded portion 22 of a check valve device, embodying an inwardly opening check valve 23, to engage upon a seat 24. The check valve device is preferably of the construction usually employed upon pneumatic tires, and the invention is in no sense restricted to the precise form of check valve device employed, the one shown being used simply for the purpose of illustration. The tubular body 20 has its outer end covered by a removable cap 25. The bore of the tubular body is provided with a radial port 27, in communication with a longitudinal port 28, formed through the tubular body portion 15 and necks 17. The port 28 is in permanent free communication with the two cells 14. The port 28 has a restricted or reduced diameter and I have found that by giving the same a diameter of about one-fourth of an inch, that satisfactory results are obtainable. By providing the restricted port 28, both cells 14 are in permanent free communication, whereby they may receive air pressure from the common inflating valve and both cells will be inflated at the same pressure. When the load is suddenly shifted to one shoulder only, of the horse, the restricted port 28 will retard the sudden rush of air pressure from one cell to the other, and properly and gradually equalize the pressure in the cells in proportion to the load.

The device 15 is located beneath the bottom of the continuous bead 12, and is protected thereby, and covered by a heavy flap 29, which may be stitched to the bead 12. This device is, therefore, fully protected and is out of the way of other parts of the harness.

In the use of the collar, it is applied to the horse in the usual manner. When it is

desired to inflate the collar, the cap 25 is removed and a pump suitably connected with the tubular body 20 through the medium of the usual hose. Air pressure will pass through the body, port 27, and port 28, to both cells 14, which will be inflated at the same pressure. After inflation, the hose is removed from the tubular body and the cap 25 returned in place upon this tubular body and a flap 29 employed to cover the cap 25. Both cells 14 are in permanent communication with each other and as the load varies slightly upon the shoulders of the horse, the pressure may pass through the contracted port 28, from one cell to the other. However, should the load be greatly or rapidly increased upon one shoulder, the contracted port 28 will prevent the sudden passage of air pressure from one cell to the other. Hence the contracted port will serve to automatically equalize the pressure in the two cells.

It is to be understood that the form of my invention, herewith shown and described, is to be taken as a preferred example of the same, and that various changes in the shape,

size and arrangement of parts may be resorted to without departing from the spirit of my invention, or the scope of the subjoined claim.

Having thus described my invention, I claim:

In a horse collar, an outer casing comprising a pair of side sections, cells arranged in the side sections and adapted to be inflated, a separate coupling arranged at the bottom of the side sections and having extensions inserted within the ends of the cells, said coupling having a contracted bore of unobstructed uniform diameter throughout its length and placing the cells in permanent communication with each other for equalizing the pressure in the cells and retarding the sudden rush of air from one cell to the other, and check valve inflating device connected with the coupling and leading into the bore without obstructing such bore, whereby both cells may be simultaneously inflated at the same degree of pressure by the air passing through the contracted bore.

In testimony whereof I affix my signature.
INGEBERT J. THOMSEN.
